DESIGN.

—o—
F. MANKEY.

PANEL.

No. 16,233.

Patented Sept. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,233, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

The design consists—

10 First. Of a row, longitudinally the panels, of truncated pyramidal elevations, A, alternating with elongated truncated pyramidal elevations B. The sides of said elevations are rounded, and on the summit of each is a flat 15 rectangular elevation, C.

Second. Of a row, longitudinally the panel, of elevations, D, similar to elevations B, but standing transversely the panel, and alternately with rectangular pyramidal elevations E, 20 having rounded sides and larger in size than the elevations A.

Third. Of a row of elevations, F G, similar to the row first above mentioned.

The second row of elevations, before referred to, is arranged, as shown, between the first and third rows. Intermediate transverse channels, H, and longitudinal channels I, of rectangular cross-section, separate the said elevations.

On the upper surfaces of the elevations E, I 30 form ornamental figures, such as herein shown as consisting of several concentric circles appearing upon each of said elevations.

The number of the several elevations in a panel is not material, provided they are formed 35 and arranged substantially as represented.

I claim—

1. The design for an ornamental panel, substantially as herein shown and described, which consists in a longitudinal row of elevations, A, 40 alternating with elevations B, a second row of similar figures, F G, and between said rows a row of elevations, D and E, with intermediate channels, H and I.

2. The design for an ornamental panel, substantially as herein described and shown, which consists in a longitudinal row of elevations, A, alternating with elevations B, a second row of similar figures, F G, and between said rows a row of elevations, D and E, and upon each of 50 said elevations D and E an ornamental figure, (such as herein shown,) with intermediate channels, H and I.

FREDERICK MANKEY.
